UNITED STATES PATENT OFFICE.

FRANK E. LEITCH, OF HACKENSACK, NEW JERSEY, ASSIGNOR TO WILLIAM CAMPBELL
WALL PAPER COMPANY, OF HACKENSACK, NEW JERSEY, A CORPORATION OF
NEW JERSEY.

DESIGN FOR WALL-PAPER.

43,623.

Specification for Design.

Patented Feb. 25, 1913.

Application filed December 13, 1912. Serial No. 736,625. Term of patent 3½ years.

To all whom it may concern:

Be it known that I, FRANK E. LEITCH, a citizen of the United States, residing at Hackensack, New Jersey, have invented a new, original, and ornamental Design for Wall-Paper, of which the following is a specification, reference being had to the accompanying drawings, forming part thereof.

I claim:

The ornamental design for wall paper, as shown.

In testimony whereof I have signed this specification in the presence of two subscribing witnesses.

FRANK E. LEITCH.

Witnesses:

BARDIN E. HIGBY,
S. MARSHALL.
